(57) **CLAIM**

The ornamental design for a motorized surf board as shown and described.

DESCRIPTION

FIG. 1. is a top perspective view of a first embodiment of a motorized surf board;

FIG. 2. is a bottom perspective view thereof;

FIG. 3. is a front view thereof;

FIG. 4. is a back view thereof;

FIG. 5. is a left side view thereof;

FIG. 6. is a right side view thereof;

FIG. 7. is a top view thereof;

FIG. 8. is a bottom view thereof;

FIG. 9. is a top perspective view of a second embodiment of a motorized surf board;

FIG. 10. is a bottom perspective view thereof;

FIG. 11. is a front view thereof;

FIG. 12. is a back view thereof;

FIG. 13. is a left side view thereof;

FIG. 14. is a right side view thereof;

FIG. 15. is a top view thereof; and,

FIG. 16. is a bottom view thereof.
